METHOD OF PROTECTING ELECTRIC BLASTING CAPS

Charles M. Blackburn and Frederick R. Seavey, Alton, Ill., assignors to Olin Mathieson Chemical Corporation, a corporation of Virginia

Application November 16, 1956, Serial No. 195,974

1 Claim. (Cl. 102—28)

This invention relates generally to electric blasting caps, and particularly to the treatment, prior to packaging, of the terminal portions of the lead wires for such blasting caps.

The ordinary electric blasting cap of commerce is provided with long lengths of lead wire, the free ends of which are adapted to be connected into the firing circuit when the blasting cap is placed in position to detonate explosive.

In the packaging of electric blasting caps for shipment and handling, it is important to protect the cap from the possibility of accidental detonation which might occur by virtue of the lead wires coming in contact with stray electrical currents and other sources of electrical energy. Protection of the caps in this respect involves shunting or otherwise temporarily, i. e., for the duration of the shipping and handling process, electrically connecting together the respective lead wires near their free ends, as well as the provision of an insulating cover about any naked portions of the wire.

The object of the present invention, generally stated, is to provide a method of treating the lead wires of electric blasting caps and packaging the same whereby to protect the device in shipment and to facilitate its connection into a firing circuit.

Another object of the invention is to provide an electric blasting cap wherein, as the shunt is removed, the lead wires are bared of insulation at their terminal portions.

Other objects will become apparent to those skilled in the art when the following description is read in connection with the accompanying drawings, in which:

Figure 1 is a view in side elevation of a packaged electric blasting cap constructed in accordance with the present invention, part of said package being shown in section to reveal the relationship of the several parts;

Figure 2 is an enlarged detail view showing the free ends of the lead wires of the blasting cap shown in Figure 1;

Figure 3 is an end view of the shunting device shown in Figure 1;

Figure 4 is a view corresponding to Figure 1, but showing a different embodiment of the invention; and

Figure 5 is an enlarged detail view of the free ends of the lead wires treated as shown in Figure 4.

The present invention contemplates that the lead wires of the usual electric blasting cap have their free ends treated so that the insulation covering the terminal two or three inches is severed from the insulation covering the balance of the wires, and the terminal portion slightly separated from the main portion by slipping the separated piece lengthwise of the wire so that the separated portion overhangs the end of the conductor. A gap between the terminal portion of insulation and the main portion of insulation is thus formed whereat the conductors within the lead wires are bare. The invention contemplates that the lead wires be electrically shunted at said gap, and this may be accomplished by engaging the two bared conductors and suitably but temporarily securing them in en-

2

gagement, or by applying an auxiliary conductive clip to the bared conductors at said gap. In either event, it is desirable to surround the connection between the bared conductors with a protective member of non-conducting material in order to prevent contact with live electrical parts. Furthermore, it is desirable to form the connection between the lead wires at the gap in such manner that the member holding the wires together may be gripped and slipped endwise of the wires toward their free end to strip therefrom not only the holding member but also the terminal portions of insulation. In order to assure the ease of the latter operation, it is desirable to protect the terminal portions of the lead wires so that they remain straight during shipment and handling and until the cap is ready to be connected into its firing circuit. The term "straight," as used in connection with the terminal portions of the lead wires in this specification and the appended claims, is not used in its geometric sense, but rather connotes the freedom from kinks or abrupt turns or bends, which would interfere with the free slipping of the original insulation covering from the wires.

Referring now to Figures 1, 2, and 3 of the drawings for an illustrative embodiment of the invention, an electric blasting cap 1 of any suitable construction is provided with a pair of lead wires 2 and 3, which are of substantial length and coiled about a tubular spool 4 in a manner well known to those skilled in the art.

The lead wires 2 and 3 are of the type generally employed in the art wherein a conductor strand is encased in insulation, which may be plastic, rubber textile, or any other suitable material, severed increments of which retain a tubular form.

The invention contemplates that the free ends of the lead wires 2 and 3 be treated so as to separate the insulation at the terminal portions thereof from the insulation upon the balance of the wires. The operation is shown most clearly in Figure 2. The two or three inches of lead wire at the extremities thereof is herein referred to as the terminal portion, by which is meant the portion of the wire usually stripped of its insulation in order to make the electrical connections into the firing circuit. Between the terminal portion and the main portion of the lead wires, the insulation is cut, as for example, at lines 5 and 6 of wires 2 and 3, respectively. The cutting operation may be accomplished with any of the well known tools available for the purpose, but is preferably done in such manner that the conductor element within the lead wires is not mutilated. The lines of cut 5 and 6 permit the short sections of insulation 7 and 8 about the terminal portions of wires 2 and 3, respectively, to be slipped lengthwise of the wires, thus forming a gap 9 between the shoulders of insulation formed by the cuts 5 and 6 between the main portions of insulation and the terminal portions 7 and 8. At the gap 9, the conductor within lead wire 2 is bared of insulation, as shown at 10, and the conductor within lead wire 3 is bared of insulation, as shown at 11. When the portions of insulation 7 and 8 are slipped lengthwise as above indicated, the ends thereof overhang and thus protect the tips 12 and 13 of the conductors within the lead wires 2 and 3, respectively. As above indicated, it is desirable to maintain the conductors within the terminal portions of insulation 7 and 8 straight.

After the insulation on the terminal portions of the lead wires 2 and 3 has thus been separated from the insulation on the main portions thereof, the wires are connected together at sections 10 and 11. As shown in Figures 1 and 3, the connection takes the form of a split metallic cup 14, which is fitted within spool 4. The cup 14 has its bottom split to provide two spring members 15 and 16, which will yield sufficiently to per-

mit the lead wires to be passed therebetween. As shown in the drawings, the parts 15 and 16 are flared in a direction such that the force exerted incident to forcing the tip of the lead wires inwardly therethrough readily separates the parts 15 and 16, but the reverse movement tends to draw said parts together. The terminal portions of the lead wires are passed through cup 14 so as to lie on the interior of spool 4 with the parts 15 and 16 engaging the bared conductors at 10 and 11. Thus, when the cup 14 is formed of conductive material, the lead wires are thereby electrically shunted.

The extremities of the lead wires may be passed through the cup 14 before the latter is inserted in spool 4, or afterwards, as is desired, it being unnecessary to rigidly secure the cup 14 within the spool 4. When the user is ready to connect the lead wires 2 and 3 into the firing circuit, the spool 4 may be gripped in one hand in such manner that a thumb or forefinger prevents withdrawal of cup 14 from the interior of the spool. With the adjacent portions of lead wires 2 and 3 gripped in the other hand and pulled in the withdrawing direction, it is evident that the tips of spring members 15 and 16 will engage the shoulder formed on terminal portions 7 and 8 of the insulation by cuts 5 and 6 and prevents the latter from being withdrawn concurrently with the lead wires. Hence, as the wires are withdrawn, the terminal portions of insulation 7 and 8 are completely removed from the conductors therein contained and, as the wires are withdrawn from the spool 4, they are ready for connection into the firing circuit without any further treatment.

In the embodiment shown in Figures 4 and 5, the lead wires 2 and 3 are treated in the same manner as described above with reference to Figure 2, so as to provide terminal portions of insulation 7 and 8 spaced from the main portions of insulation on wires 2 and 3. In this embodiment, however, the electrical connection of the lead wires at the gap between the two separated portions of insulation is accomplished by bringing the wires into physical engagement with each other at the aforesaid gap. With the wires in physical contact, the same may be temporarily fastened together in any suitable way, as for example, by tying them with a string, thread, or ribbon, or by applying a sticker, clip, or clamp, so as to maintain the bared parts in electrical connection during the process of shipping and handling. As shown in the drawings, the bared sections of conductor are held in contacting relation by being bound by a layer of non-conductive thread 20. The non-conductive thread 20 not only assures the maintenance of electrical contact between the two conductors, but prevents contact therewith of live electrical parts. The invention is, however, not limited to the utilization of non-conductive material for connecting the parts together in this manner, but, when conductive material is utilized for

this purpose, it is desirable to tuck the terminal portions of the lead wires, including the binding 20, into the interior of spool 4, in contrast to the exterior position shown in Figure 4. Moreover, when the tie is of conductive material, it is unnecessary to hold the bared sections of wire in physical contact with each other.

When it is desired to connect the blasting cap into its firing circuit, the binding 20 may be gripped between the thumb and forefinger of one hand, while the main portions of the lead wires are gripped in the other hand, and the two drawn apart, thus concurrently stripping the lead wires 2 and 3 not only of the binding 20, but of the terminal portions of insulation 7 and 8. Thus in both embodiments the outer ends of the lead wires are protected by the overhanging insulation, the bared increments are electrically connected together, and the latter are protected from contact with live electrical members either by being enclosed within the spool 4, or by being wrapped with non-conductive material 20.

From the foregoing description those skilled in the art should readily understand the construction, operation, and advantages of the invention. While two complete embodiments have been disclosed in detail and other alternatives suggested, it is not to be understood that the invention is limited to the details described. On the contrary, it is to be distinctly understood that the foregoing disclosure is merely for illustrative purposes, and that such modifications and variations thereof as do not depart from the spirit of the invention are contemplated by and within the scope of the appended claim.

Having thus described the invention, what is claimed and desired to be secured by Letters Patent is:

The method of protecting electric blasting caps having insulated lead wires which comprises making a cut through the insulation on the lead wires to separate the insulation on the terminal portions of the lead wires from the insulation on the remainder of the wires, slipping the separated terminal section of insulation endwise of the wires to bare a short increment of wire, all without removing the insulation from the wires, and, with the separated section of insulation overlapping the ends of the wires, electrically short-circuiting the bared increments of the lead wires, and packing the caps with the short-circuited increments enclosed by non-conductive material.
